UNITED STATES PATENT OFFICE.

CLEVELAND G. DAVIS, OF MANISTEE, MICHIGAN.

STOVE-LEG.

No. 889,298.

Specification of Letters Patent.

Patented June 2, 1908.

Application filed December 28, 1907. Serial No. 408,417.

To all whom it may concern:

Be it known that I, CLEVELAND G. DAVIS, citizen of the United States, residing at Manistee, in the county of Manistee and State of Michigan, have invented certain new and useful Improvements in Stove-Legs, of which the following is a specification.

This invention contemplates certain new and useful improvements in stove legs and the object of the invention is an improved 10 caster which is designed to be attached to a stove leg to adapt the stove to be easily trundled when desired, and which may be conveniently raised and held in a novel 15 manner out of operative position in order to render the stove stationary after it has been set in place.

With this and other objects in view that will more fully appear as the description 20 proceeds, the invention consists in certain constructions and arrangements of parts that I shall hereinafter fully describe and claim.

For a full understanding of the invention and the merits thereof reference is to be had 25 to the following description and accompanying drawing, in which:

Figure 1 is a perspective view of a stove showing my improved stove legs applied thereto. Fig. 2 is a vertical section of a 30 stove leg showing the caster in an operative position. Fig. 3 is a similar view showing the caster in raised position.

Corresponding and like parts are referred to in the following description and indicated 35 in all the views of the accompanying drawing by the same reference characters.

My improved caster is described and illustrated in connection with a stove leg A, and comprises a relatively broad supporting arm 40 1 which is preferably constructed of suitable spring material and is formed at one end with a sleeve 2 by means of which it is pivotally mounted on a bolt 3 extending across the inner face of the stove leg A and secured between 45 the sides thereof. A cupped disk 4 is rigidly secured to the other end of the arm 1 and is designed to receive the foot of the stove leg. To the bottom of this disk is secured a plate 5, and a caster frame 6 carrying

a caster proper 7, is swiveled to the said 50 plate, anti-friction bearings 8 being interposed between the plate and the caster frame, as shown.

In order to remove the caster from operative position, the adjacent end of the stove 55 is raised and the cupped disk is sprung out of engagement with the foot of the stove leg, as is permitted by the spring construction of the supporting arm. The device is swung upwardly until it is received in the interior 60 chamber of the stove leg, as clearly shown in Fig. 3, and is then wedged between the upper end of the stove leg and the bolt, such wedging obviously bowing the spring arm which thus exerts its tension to hold the device 65 securely in its raised position. In this raised position the caster is substantially out of sight and will not tear a broom when sweeping or otherwise get in the way.

Having thus described the invention, what 70 I claim is:

1. In combination with a stove leg, a device of the character described comprising a spring supporting arm pivotally connected at one end to the stove leg, a disk secured to 75 the other end of said arm, and a caster mounted on the disk, said device being designed to be wedged between the pivoted end of the arm and the upper end of the stove leg, as and for the purpose set forth.

2. In combination with a stove leg, a device of the character described comprising, a bolt secured to the stove leg, a spring supporting arm formed at one end with a sleeve mounted on said bolt, a disk secured to the 80 other end of the arm and designed for operative engagement with the foot of the stove leg, and a caster attached to the disk, said device being adapted to be wedged between the upper end of the stove leg and the bolt 85 90 whereby to hold the caster in an inoperative position, as and for the purpose set forth.

In testimony whereof I affix my signature in presence of two witnesses.

CLEVELAND G. DAVIS. [L. S.]
